UNITED STATES PATENT OFFICE.

OTTO M. KNOBLOCK, OF SOUTH BEND, INDIANA.

ELECTRIC SWITCH.

1,080,563.

Specification of Letters Patent.

Patented Dec. 9, 1913.

Application filed July 11, 1912. Serial No. 708,747.

To all whom it may concern:

Be it known that I, OTTO M. KNOBLOCK, a citizen of the United States, residing at South Bend, in the county of St. Joseph and State of Indiana, have invented certain new and useful Improvements in Electric Switches, of which the following is a specification.

This invention relates to improvements in electric switches and has for its particular object, to provide a simple and inexpensive device, constructed with a few parts adapted to coöperate with each other to this end.

A further object is to provide an effective switch, wherein the blade is positively forced into close engagement with the terminal contacts.

These and other objects hereinafter described, are attained by the means illustrated in the accompanying drawing, in which:

Figure 1 is a perspective view of my improved switch, showing the single throw type. Fig. 2 is a like view of the base of said switch. Fig. 3 is a plan view of the same switch. Fig. 4 is a cross section on the line 4—4 of Fig. 3. Fig. 5 is a similar view on the line 5—5 of Fig. 3, and Fig. 6 a view of a two throw switch.

Similar reference numerals in all of the figures of the drawing designate like parts.

Referring to Figs. 1 to 5, inclusive, of the drawing, the non-conductor base 7 is recessed along one edge, as shown at 8, forming a high portion 9 and a low portion 10, said high portion 9 having shallow transverse grooves 11 formed therein. These grooves 11 are adapted to receive the contact plates 12, and said plates are provided with threaded apertures, which are engaged by the screws 14 to retain them in said grooves, and said screws are inserted from the under side of the base and project above said contact plates and adapted to receive the nuts 15. Plates 12 are reversible, as shown clearly in Figs. 1 and 3, in one instance, the apertured end extends over the lower portion of the base and forms part of the support for the pivoted end of the blade 16, and in

the other instance, the apertured end lies in one of the grooves 11, so that its free end can project over the lower portion of the base to form a contact to be engaged by said blade 16. The apertures 17 in the base and through which the screws 14 pass, are bored and reamed and are enlarged at their lower

ends to form recesses for the heads of the screws. The base is also provided with apertures 18 through which screws can be passed to secure the switch in position. 60 Blade 16 is pivoted on its screw 14 between its plate 12 and the lower portion of the base, and a washer 18' is placed between it and the base. Constructed as thus described, a movement of the blade 16 in one 65 direction will bring it beneath the free end of one of the plates 12 and to positively force said blade into engagement with said plate a boss 19 is formed on the lower portion 8 of the base and over which the blade 70 passes. The outer edge of the boss 19 is beveled or inclined to positively direct the blade beneath the contact plate, and the incline preferably ends beneath the plate, whereby the edge of the blade can enter 75 slightly under the edge of the plate, as shown in dotted lines in Fig. 3, before it is forced in contact with said plate.

In assembling the parts, the screws 14 are inserted in their apertures from the under side of the base, as before mentioned, and engage with the threaded apertures of the contact plates 12, said plates being drawn into the grooves 11 by the rotation of the screws. 80

The two throw switch shown in Fig. 6, is shown approximately triangular in form, having a lower portion 20; with the contact plates and blade mounted precisely in the same manner as shown in the single throw 90 switch above described.

It will be understood that the shape of the switch can be arranged as desired.

The extension of the screws 14 which retain the contact plates 12 in the grooves 11, 95 together with the nuts 15, form the terminals for securing the wires to the switch.

It will be observed from the above description, that a simple, inexpensive and effective switch is secured, easy to assemble 100 and having few parts.

Having thus described my invention, what I claim as new is:

1. A switch, comprising a base having a grooved upper portion and a lower portion, 10 the bottom of said grooves being above the surface of said lower portion, contact plates seated in said grooves and projecting over said lower portion, means for securing said plates in said grooves, a blade pivoted on 11 one of said securing means between one of said plates and said lower portion, and a

boss on the lower portion whose top surface lies in a plane lower than the bottom of said grooves and in alinement with one of the plates for forcing said blade into engagement therewith.

2. A switch, comprising a base having a grooved upper portion and a lower portion, the bottom of said grooves being above the surface of said lower portion, contact plates seated in said grooves and projecting over said lower portion, means for securing said plates in said grooves, a blade pivoted on one of said securing means between one of said plates and said lower portion, and a

boss on said lower portion whose top surface lies in a plane lower than the bottom of said grooves and in alinement with one of said plates for forcing said blade into engagement therewith, said boss having an inclined front edge which ends beneath said plate.

In testimony whereof I affix my signature in presence of two witnesses.

OTTO M. KNOBLOCK.
